UNITED STATES PATENT OFFICE.

DOUGLAS WHITAKER, OF LEICESTER, ENGLAND.

SHIELD TUNNELING-MACHINE.

1,311,142.

Specification of Letters Patent.

Patented July 22, 1919.

Application filed May 13, 1919. Serial No. 296,950.

To all whom it may concern:

Be it known that I, DOUGLAS WHITAKER, subject of the King of Great Britain, residing at Leicester, in the county of Leicester, 5 England, have invented certain new and useful Improvements in or Relating to Shield Tunneling-Machines, of which the following is a specification, reference being had therein to the accompanying drawing.

10 This invention relates to tunneling machines and concerns more particularly, though not exclusively, those of the self contained type, *i. e.*, wherein the driving elements and auxiliary devices are arranged 15 within the cylindrical outer case or other body or frame.

The invention concerns tunneling machines of the kind wherein the rotatable cutting or boring head is mounted and arranged so that it may be displaced relatively 20 to the case, body or frame of the machine when desired for the purpose of changing the direction of advancement of the machine.

25 The present invention comprises, in a tunneling machine having a displaceable cutter head as aforesaid, an arrangement wherein the said head and its shaft, the motor, driving gearing and associated parts, are carried by a structure which at or near the rear end is supported by a gimbal mounting and at or near the front end is held in position in the case or other body or frame by devices which are capable of adjustment to 30 vary the position of said front end therein for the purpose of displacing the head.

The devices for adjusting the front end of the structure may in one construction consist of sets of oppositely disposed screws. In 40 a modified form the said adjusting means may consist of screws for effecting lateral adjustment and a lever, link and screw for the vertical adjustment.

To enable the invention to be clearly and 45 readily understood reference will be made in the following further description to the accompanying drawing, wherein:

Figure 1 is a side elevation partly sectional, of a tunneling machine of the self 50 contained type having an arrangement of the displaceable cutter head according to this invention.

Fig. 2 is a cross sectional view on the line 1—1 of Fig. 1 looking toward the left.

55 Fig. 3 is a similar view on the line 2—2 of Fig. 1 looking toward the right.

Fig. 4 is a similar view to Fig. 3 showing a modified arrangement.

In the concrete example illustrated the invention is shown applied to a tunneling machine of the self contained type wherein the driving elements and auxiliary devices are arranged within a body framework which fits within and is advanced along a cylindrical lining placed in position in sections 60 behind the cutter head.

Referring to Fig. 1, 2 is the cutter head, 3 is the cutter shaft and 4 is the body or frame of the machine.

The frame is fitted with wheels 5 and 70 rollers 6 which enable the complete machine to advance along the cylindrical lining 7, each section of which is placed in position underneath the shield 8 carried by the frame 4.

75 According to the present invention, the cutter shaft 3 with the head 2, the motor 9, gear box 10, driving means 11, and associated parts are carried by a longitudinal structure 12 (Figs. 1, 2,) and this is supported within the frame 4 in such a manner that it may be moved therein for the purpose of displacing the cutter head 2. For this purpose, the said structure 12 is at a suitable point near the end remote from 80 the cutter head, carried by a gimbal which will admit of the opposite (front) end having universal movement. The said movable end is held in position by or between devices which are capable of adjustment to 85 vary the position of the structure 12 and hence that of the cutter head 2 relatively to the normal concentric position of the latter.

90 The gimbal mounting comprises, as shown 95 in Figs. 1 and 2, a gimbal frame 13 arranged to turn on a vertical axis consisting of pins 14 in fitments 15 situated above and below the frame 13 and attached to transverse bars 16 forming part of the body 100 frame 4 of the machine. The longitudinal structure 12 is movable on a horizontal axis in the gimbal frame 13 constituted by pivot pins 17. Thus when the cutter head 2 is raised and lowered, the structure 12 turns on the pins 17, and when it is displaced laterally the frame 13 turns on the pins 14.

105 One form of means for holding and shifting the movable end of the structure consists of screws (Figs. 1 and 3) comprising 110 vertically disposed screws 18 situated one above and one below the structure, and hori-

zontally disposed screws 19 situated on opposite sides of said structure. These screws are carried by the frame 4 and it will be obvious that by adjusting same, *i. e.*, slackening one and tightening the other of either or both sets, the front end of the structure 12 may be displaced in the direction desired.

In another form of means for holding and shifting the structure 12' (Fig. 4), 10 which corresponds in function with the structure 12 of Figs. 1, 2 and 3, oppositely situated screws 20 for effecting lateral displacement are provided, but in this case the movable front end of the structure 12 15 is supported by a link 21 attached to one arm 22 of a bell-crank lever 23 pivotally mounted on the frame 4 at 24 its other arm 25 engaging a nut 26 on a screwed shaft 27.

The shaft 27 may be rotated from either 20 side of the frame 4 by a hand-wheel 28 and when so actuated moves the nut in one direction or the other and through the medium of the bell-crank lever 23 and link 21 raises or lowers the structure 12'. The 25 vertical movement of the structure 12' takes place between the opposing side screws, the link 21 swinging on the arm 22 when the structure is displaced laterally by an adjustment of said screws.

30 It will be understood that the cutter shaft 3, motor 9, and other parts of the machine which it is desirable or necessary shall have a constant relationship to each other are supported directly or indirectly by the lon-

gitudinal structure 12 or 12' and therefore 35 move with the same when it is adjusted to displace the cutter head 3, relatively to the body or frame 4.

In applying the invention to tunneling 40 machines of the kind wherein the shield is of cylindrical form and constitutes a case 45 completely inclosing the driving elements and other parts, the displaceable structure or part carrying said elements and parts and the cutter head is mounted in the cylindrical case in the same manner as already described with reference to the mounting of the structure or part in the frame 4.

I claim:

A tunneling machine comprising a main 50 frame adapted to move lengthwise of a tunnel, a cutting head, a shaft upon which said head is mounted, a structure carried by the main frame for the support of said shaft, gimbal joint connections between the rear 55 end of the said structure and the main frame, adapted to allow the shaft to be diverted from axial alinement with the tunnel and laterally and vertically adjustable means for supporting said shaft near its 60 forward end.

In testimony whereof I affix my signature in presence of two witnesses.

DOUGLAS WHITAKER.

Witnesses:

R. W. C. TAYLOR,
GEORGE LESTER.
